(57) **CLAIM**

We claim the ornamental design for a metal roofing, as shown and described.

DESCRIPTION

FIG. 1 is a top perspective view of a metal roofing;
FIG. 2 is a bottom perspective view of the metal roofing of FIG. 1;

FIG. 3 is a top plan view of the metal roofing of FIG. 1;
FIG. 4 is a bottom plan view of the metal roofing of FIG. 1;
FIG. 5 is a front elevational view of the metal roofing of FIG. 1;

FIG. 6 is a rear elevational view of the metal roofing of FIG. 1;

FIG. 7 is a first side elevational view of the metal roofing of FIG. 1;

FIG. 8 is a second side elevational view of the metal roofing of FIG. 1;

FIG. 9 is a top perspective view of another embodiment of a metal roofing;

FIG. 10 is a bottom perspective view of the metal roofing of FIG. 9;

FIG. 11 is a top plan view of the metal roofing of FIG. 9;
FIG. 12 is a bottom plan view of the metal roofing of FIG. 9;

FIG. 13 is a front elevational view of the metal roofing of FIG. 9;

FIG. 14 is a rear elevational view of the metal roofing of FIG. 9;

FIG. 15 is a first side elevational view of the metal roofing of FIG. 9; and,

FIG. 16 is a second side elevational view of the metal roofing of FIG. 9.

(Continued)

The broken lines in Embodiment 1 illustrate grooves in the metal roofing that form no part of the claimed design.

1 Claim, 10 Drawing Sheets
